WIRE LINE GUIDE

William K. Holleron and William L. Buckley,
Victoria, Tex.

Application April 19, 1947, Serial No. 742,688

5 Claims. (Cl. 254—190)

1

This invention relates to a guide for wire lines. The invention is particularly adapted for use on well drilling rigs for guiding the wire line, or rope, which leads from the drawworks drum and operates over the derrick crown block sheaves.

An object of the invention is to provide a guide of the character described which will move automatically as the wire line is wound onto, or unwound from, the drum of the drawworks so as to maintain itself in proper position but which will limit the lateral movement of the line thus preventing it from swinging about the derrick and interfering with, or injuring, the workmen.

It is another object of the invention to provide a line guide of the character described which is of sturdy construction and which will restrain the irregular movements of the line but which is sufficiently flexible to allow the necessary movements of the line.

Other objects and advantages of the invention will be apparent from the following specification which is illustrated in the accompanying drawings wherein—

Figure 1 is a side elevation of the guide shown partly in section.

Figure 2 is an end view thereof.

Figure 3 is an enlarged, sectional view taken on the line 3—3 of Figure 1.

Figure 4 is an enlarged, cross-sectional view taken on the line 4—4 of Figure 1, and

Figure 5 is a fragmentary, sectional view of another type of plunger which may be employed.

Referring now more particularly to the drawings, wherein like numerals of reference designate similar parts in each of the figures, the numeral 1 designates one of the corner legs of a well derrick.

These corner legs are connected by suitable cross-girts, or braces, 2.

Fastened to a cross brace 2 and extending inwardly therefrom there is a bracket 3.

Supported by the inner end of the bracket there is a rectangular frame which, in the present illustration, is formed of upper and lower channel irons 4, 5 which may be connected, at one end, by a cross-connecting bar 6 and secured between the other ends of which there is a controlling cylinder 7.

Operating in said cylinder there is a piston 8 to which the piston rod 9 is secured. This piston rod extends outwardly through the inner end of the cylinder and is sealed with said inner end by means of a stuffing box 10 therearound.

On the outer end of said rod there is a car-

2

riage frame 11 in which there is mounted the upper and lower carrier wheels 12 and 13 which run in the longitudinal grooves 14 and 15 in the upper and lower channel irons. Piston rod and piston are thus allowed to move back and forth longitudinally of the frame, or track, but are prevented from turning.

As the wire line is wound onto the drum it will move along laterally in the direction indicated by the arrow in Figure 1 and as it is unwound from the drum it will move laterally in the opposite direction.

The cylinder 7 is filled with a suitable liquid, such as oil.

15 In a preferred form of the invention there is a transfer pipe 16 leading from the outer end of the cylinder and entering the opposite end thereof and this pipe is provided with a valve 17 by means of which the pipe may be opened and closed. During the operation of the guide the valve 17 is open and as the piston 8 moves in one direction the liquid in front of it is transferred through the pipe 16 into the cylinder behind the piston and vice-versa.

20 There is a reserve supply tank 18 filled with oil and leading from it there is an outlet pipe 19 formed with the branches 20, 20 which enter the pipe 16 on opposite sides of the valve 17.

These branches 20 are equipped with valves 21, 21 which are normally closed but which may be opened to supply additional oil into the cylinder on either side of the piston as required.

25 The oil in the cylinder 7 stabilizes the movement of the wire line as it is wound onto, or unwound from, the drum of the drawworks.

30 As shown in Figure 5, the piston 8a is formed with one, or more, passageways 17a therethrough. In case this type of piston is used the valve 17 may also be maintained closed and upon movement of the piston 8a the liquid in the cylinder may move from one side of the piston to the other side through the passageways 17a. The embodiment illustrated in Figure 5 may be used in lieu of the form shown in Figure 1 if desired.

35 There is an arm 22 one end of which is formed with a sleeve 23 which surrounds, and is spaced from, the piston rod 9 and whose ends are internally threaded to receive the plugs 24, 24 which closely surround the rod 9 and are screwed into the respective ends of the sleeve 23.

40 Within the sleeve 23 and fitted around the rod 9 there is a sleeve shaped liner 25 formed of rubber or other resilient material which rebounds upon distortion. The plugs are screwed 45 tightly against the ends of the liner 25 to cause

it to expand and grip both the rod 9 and the sleeve 23 so that the arm 22, if partly rotated relative to the rod 9, will cause distortion of said liner and the rebound of the liner will restore the sleeve to its original position.

The free end of the arm 22 is provided with a frame 26 which is provided with the upper pair of opposed rollers 27, 27 and a lower pair of opposed rollers 28, 28 and the cable, or wire line, 29 to be guided, passes between the rollers of the respective pair, as shown in Figures 1 and 2. Also mounted in the frame 26 there is an intermediate pair of opposed rollers 30, 30. The cable 29 also passes between these rollers 30. The cable may therefore move freely longitudinally as it is wound onto or unwound from the drum.

The movement of the cable in a direction at right angles to the piston rod 9 will be limited by the arm 22 and the side swaying or slapping of the line will thus be greatly reduced although the guide is sufficiently flexible to allow the necessary movements of the line while carrying on drilling operations.

The drawings and description are illustrative merely while the broad principle of the invention will be defined by the appended claims.

What we claim is:

1. A line guide comprising, a supporting structure, a liquid containing cylinder thereon, a piston in the cylinder, there being a by-pass conduit through which the liquid in the cylinder may by-pass the piston, a piston rod connected to the piston and extending out beyond the cylinder, an arm carried by said rod, yieldable means connecting the arm to the rod and normally holding the arm in a selected position relative to the rod and guiding means on the arm through which the line works.

2. A line guide comprising, a supporting structure, a fluid containing cylinder thereon, a piston in the cylinder, there being a by-pass conduit through which the fluid in the cylinder may by-pass the piston, a piston rod connected to the piston and extending out beyond the cylinder, an arm yieldingly connected to the piston rod and guiding means on the arm through which the line works.

3. A line guide comprising, a supporting struc-

ture, a fluid containing cylinder thereon, a piston in the cylinder, a conduit through which the fluid in the cylinder may by-pass the piston, means for controlling the passage of fluid through

5 said conduit, a piston rod connected to the piston and extending out beyond the cylinder, an arm carried by the rod, resilient means connecting the arm to the rod arranged to be distorted upon application of pressure to the arm and which will rebound upon removal of said pressure and line guiding means on the arm through which the line works.

4. A line guide comprising, a supporting structure, a fluid containing cylinder thereon, a piston in the cylinder having a conduit therethrough through which the fluid in the cylinder may by-pass the piston, a piston rod connected to the piston and extending out beyond the cylinder, an arm yieldingly connected to the rod, guide means on the arm through which the line works, a track on the supporting structure and a carriage movable along the track and attached to the extended end of the piston rod.

5. A line guide comprising, a supporting structure, a rod mounted to move longitudinally relative to said structure, means for controlling longitudinal movement of the rod, a sleeve around the rod, a liner within the sleeve around the rod and formed of resilient material, means for compressing said resilient material within the rod to cause it to grip the rod, an arm depending from the sleeve and line guiding means on the arm through which the line works.
